UNITED STATES PATENT OFFICE

154,419

DESIGN FOR A UTILITY CABINET

Igor Mushta, New York, N. Y.

Application December 3, 1947, Serial No. 142,943

Term of patent 14 years

(Cl. D33—19)

To all whom it may concern:

Be it known that I, Igor Mushta, a citizen of the United States of America, and a resident of the city of New York, county of Bronx, and State of New York, have invented the new, original, and ornamental Design for a Utility Cabinet, of which the following is a specification, reference being had to the accompanying drawings, forming part thereof, in which:

Figure 1 shows a perspective view of a cabinet in the closed position.

Figure 2 shows a perspective view of the cabinet with the hamper in the open position.

Figure 3 shows a perspective view of the cabinet with the top tray and one side panel in the open position.

I claim:

The ornamental design for a utility cabinet, as shown.

IGOR MUSHTA.
